ROCK DRILL

Charles F. Osgood, Claremont, N. H., assignor to
 Sullivan Machinery Company, a corporation of
 Massachusetts

Application August 12, 1941, Serial No. 406,513

6 Claims. (Cl. 255—45)

This invention relates to rock drills and particularly, but not exclusively, has reference to improvements in the feeding mechanism of a hammer rock drill of the mounted drifter type.

An object of the present invention is to provide an improved rock drill. Another object is to provide an improved rock drill feeding mechanism. A further object is to provide an improved feeding mechanism of the vibration controlled or so-called "jump feed" type operated by a vibratory action set up within the drill hammer motor during operation of the drill. A still further object is to provide improved drill feeding mechanism embodying a flexible feeding element and having novel means for maintaining the flexible feeding element under tension. Yet another object is to provide improved means for automatically yieldingly tensioning the flexible feeding element and novel means for automatically maintaining the flexible feeding element under tension. Another object is to provide an improved and extremely compact arrangement of the control means for the feeding mechanism. Yet another object is to provide an improved arrangement of the flexible control element on the drill guide and an improved arrangement of the control mechanism associated with the flexible element, whereby compactness is obtained. A still further object is to provide an improved rock drill having novel combinations and arrangement of parts. Other and further objects and their resultant advantages will be apparent after the invention becomes better understood from an examination of the specification and claims in connection with the accompanying drawings, in which one embodiment of the invention is illustrated.

In the drawings:

Fig. 1 is a side elevational view of a hammer rock drill in which the illustrative embodiment of the invention is incorporated, parts being shown in longitudinal vertical section to illustrate structural details.

Fig. 2 is an enlarged rear end elevational view of the rock drill shown in Fig. 1.

Fig. 3 is an enlarged detail view in longitudinal vertical section taken substantially on line 3—3 of Fig. 2.

Fig. 4 is an enlarged detail cross sectional view taken on line 4—4 of Fig. 1.

Fig. 5 is a cross sectional view taken on line 5—5 of Fig. 3.

Fig. 6 is a cross sectional view taken on line 6—6 of Fig. 3.

Fig. 7 is a detail sectional view taken on line 7—7 of Fig. 6.

Fig. 8 is a detail sectional view taken on line 8—8 of Fig. 6.

Fig. 9 is a detail sectional view taken on line 9—9 of Fig. 6.

In the illustrative embodiment of the invention the improved feeding means generally designated 1 is embodied in a hammer rock drill of the mounted drifter type generally designated 2. It will be evident, however, that the invention may be embodied in apparatus of various other types.

The rock drill disclosed herein comprises a drill hammer motor 3 of a conventional design slidably guided on the parallel guideways of a conventional guide shell 4, these guideways lying in common transverse planes. The guide shell has a usual bottom swivel plate 5 adapted for reception in the saddle mounting of a conventional rock drill support. The drill hammer motor 3 includes a motor cylinder 6 having a cylinder bore containing a reciprocable hammer piston 7 adapted to deliver impact blows to the shank 8 of a usual rock drill steel 9. The drill steel shank is mounted in a usual manner within a chuck carried within a front chuck housing 10 suitably secured to the motor cylinder, and the motor cylinder has a back head 11 carrying a usual throttle valve mechanism 12 for controlling the supply of motive fluid to the motor cylinder. A usual fluid distributing valve mechanism is provided for distributing the motive fluid to the opposite ends of the motor cylinder to effect reciprocation of the hammer piston in a well-known manner. The hammer piston as it reciprocates in the motor cylinder to effect the percussive actuation of the drill steel, imparts longitudinal vibrations in opposite directions to the hammer motor 3, and these longitudinal vibrations are employed to effect feeding of the hammer motor back and forth of the shell guideways as will later be described.

The improved feeding means 1 includes a flexible feed control chain 13 which lies on the bottom of the guide shell and extends longitudinally within the guide shell intermediate the shell guideways, and the shell bottom preferably has an upstanding ledgelike projection 14 extending centrally longitudinally of the shell and with which the chain engages, for guiding the chain to maintain the latter in parallelism with the shell guideways. As illustrated, the front end of the feed chain is detachably secured at 15 to the front end of the guide shell and is yieldingly

connected at its rear end to an improved automatic chain tensioning device generally designated 16, attached to the rear end of the guide shell. A feed control sprocket 17 lies within the guide shell midway between the guideways thereof as shown in Fig. 5, and this sprocket is keyed to a transverse shaft 18 arranged within the shell and journaled in suitable bearings supported within a casing 19 suitably attached to the rear head 11 of the drill hammer motor 3. The axis of rotation of the sprocket 17 is parallel to the transverse planes in which the shell guideways lie. Guide rolls 20 also journaled on transverse axes within the casing 19, are arranged at opposite sides of the feed sprocket 17 for guiding the feed chain 13 with respect thereto. Integral with the feed sprocket 17 is a sprocket 21 connected by an endless drive chain 22, extending upwardly between the shell guideways, to a sprocket 23 of a control mechanism generally designated 24, to be later described. The axis of rotation of the sprocket 17 is located below the top of the guide shell while the axis of rotation of the sprocket 23 is located a substantial distance above the top of the shell, in the manner shown in Figs. 5 and 6.

Now again referring to the improved automatic chain tensioning device 16, it will be noted that the rear end of the feed chain 13 is attached at 25 to a bolt 26 slidably guided in a bore 27 of a casing 28 which is shown as arranged with its center line in alignment with a line which is midway between the sides of the guide shell. This casing has lateral lugs 29 secured by bolts 30 to the rear end of the guide shell. Threaded on the rear end of the bolt 26 is an adjusting nut 31 and interposed between this nut and a shoulder 32 on a casing 28 is a coil spring 33. The coil spring 33 surrounds the bolt 26 and is arranged in a chamber 34 in the casing 28, and access to this chamber is attained by means of a detachable cover plate 35. Formed on the bolt 26 is a series of ratchet teeth 36 with which a spring-pressed pawl 37 engages, this pawl being arranged within a vertical bore 38 provided with a bottom closure plug 39. The pawl 37 is preferably of polygonal cross section so as to prevent rotation thereof within its bore. A coil spring 40 interposed between the plug and the pawl constantly urges the latter into engagement with the ratchet teeth. The coil spring 33 effects tensioning of the feed chain 13 and the pawl engaging the ratchet teeth maintains the feed chain under tension. If desired, the automatic tensioning device 16 may be arranged at the front end of the guide shell instead of at the rear end as disclosed, although this latter arrangement is preferred herein.

The control mechanism 24 is mounted on the casing 19 attached at the rear end of the hammer motor and is arranged above the top of the guide shell. This control mechanism includes a ratchet ring 45 rotatably mounted in a transverse bore 46 in the casing 19 and having internal ratchet teeth 47. This ratchet ring has its hub keyed to a control shaft 48 to which the control sprocket 23 is secured. This control shaft is suitably journaled within the casing 19, as shown in Fig. 6. A stationary pawl carrier 49 is arranged within the ratchet ring and is formed integral with a stub shaft 50 keyed to a cover plate 51 attached to the casing. The pawl carrier carries sets of reversible, spring-pressed pawls 52 and 53 engageable with the ratchet teeth 47 of the ratchet ring for controlling the

direction of rotation of the feed sprocket 17. For selectively rendering the set of pawls effective, a shifter annulus 54 is rotatably mounted in the casing bore 46, and has recesses 55 to permit the pawls to move into engagement with the ratchet teeth. An internal cylindric surface 56 on the shifter annulus 54 is engageable with the pawls for pressing the latter inwardly into their released position out of engagement with the ratchet teeth. For moving the shifter annulus into its different positions, a lever 57 projects within a slot 58 in the annulus and this lever is secured to a control shaft 59 rotatably mounted in the casing cover plate 51, and having a conveniently located operating handle 60. Spring-pressed plungers 61 and 62 arranged within suitably located bores in the casing cover plate are engageable with notches respectively for locking the parts in their different adjusted positions.

The mode of operation of the improved rock drill is as follows: The drill guide shell 4 may be set up at the working face by clamping the swivel plate 5 within the saddle mounting of the rock drill support. The operator may then manipulate the throttle valve mechanism 12 to effect a supply of motive fluid to the drill hammer motor 3 to actuate percussively the drill steel 9. When the drill hammer motor is running to effect percussive actuation of the drill steel, reciprocatory movement of the hammer piston 7 causes, due to the sudden reversals in the directions of movements of the piston, vibratory or recoil movements of the hammer motor alternately in opposite directions longitudinally thereof, as is well understood by those skilled in the art; resulting in alternating tendencies to movement of the hammer motor forwardly and rearwardly with respect to the guide shell. Movement of the hammer motor in the feeding direction is permitted by the ratchet and pawl mechanism, the ratchet teeth at that time slipping freely over the pawls 53 to permit rotation with the feed sprocket 17 with respect to the feed chain 13, and movement of the hammer motor in the reverse direction is checked automatically by the ratchet and pawl mechanism, the then active pawls 53 engaging the ratchet teeth, holding the ratchet ring against rotation and thereby automatically checking reverse movement of the hammer motor. It is accordingly evident that with the parts as shown the control mechanism 24 associated with the feed chain 13 and feed sprocket 17 permits intermittent step by step movement of the drill hammer motor in the feeding direction along the shell guideways while preventing movement of the drill hammer motor in the reverse direction. When the shifter annulus 54 is in the position shown in Fig. 8, the feed sprocket 17 is free to rotate in a counterclockwise direction as viewed in Fig. 3, relative to the feed control chain 13, thereby permitting forward feeding movement of the drill hammer motor along the shell guideways, the relatively stationary control chain, as the hammer motor moves forwardly, effecting such counterclockwise rotation of the feed sprocket. The reverse rotation of the feed sprocket 17 is checked automatically by the pawls 53 engaging the teeth of the ratchet ring 45, and as a result, rotation of the feed sprocket in a clockwise direction as viewed in Fig. 3 is prevented. It will thus be seen as the hammer piston 7 of the hammer motor reciprocates within the hammer motor cylinder to actuate percussively the drill steel, the jars imparted by the piston due to

the sudden reversal in the direction of movement thereof cause the hammer motor to jump step by step in a forward direction along the shell guideways, thereby feeding the drill steel toward the work. When the operator manipulates the handle 60, the shifter annulus 54 may be rotated to effect release of the set of pawls 53 shown in Fig. 7 and to permit the set of pawls 52 to move into engagement with the teeth of the ratchet ring 45. When the parts are in this reversed position, the feed sprocket 17, as viewed in Fig. 3 is free to rotate in a clockwise direction, so that as the hammer piston rapidly reciprocates within the motor cylinder, the feed sprocket 17 is free to rotate in a reverse direction relative to the feed chain, due to the jars set up by the hammer piston, the then active pawls 52 releasing automatically to permit free rotation of the feed sprocket in the reverse feeding direction, and holding automatically the feed sprocket against rotation in the opposite direction. When the shifter annulus 54 is moved into its intermediate position, both sets of pawls 52 and 53 are free to engage the ratchet teeth; and as a result, the ratchet ring together with the feed sprocket are locked against rotation in both directions, so that movement of the hammer motor along the guide shell is prevented. During the feeding operation the coil spring 33 automatically effects tensioning of the feed control chain 13 and the pawl 37 engaging the ratchet teeth 36 automatically maintains the feed chain under tension.

In lieu of the tension-maintaining ratchet disclosed, any suitable form of gripping means might be employed such as a friction cone or other frictional gripping means, and instead of the single pawl shown, any desired number of pawls may be used. Also, other means than that disclosed might be used to effect tensioning of the feed control chain such as pneumatic means, for instance of the kind embodying a fluid actuated piston contained in a cylinder. Further, intermeshing gearing or other forms of transmission means might be used instead of the endless drive chain between the two control shafts, and in place of the feed sprocket and feed control chain connections, a pulley and wire rope or cable might be used to equal advantage.

As a result of this invention, it will be noted that an improved rock drill feeding mechanism is provided, having novel arrangements of parts whereby the rock drill is rendered extremely compact and rugged in design. It will further be evident that by the provision of the automatic tensioning device associated with the control chain, the latter is always maintained under the proper tension thereby preventing the possibility of a too-loose chain and as a result, increasing the efficiency of the feed mechanism. By the provision of the tensioning spring and the associated automatic ratchet device, the feed control chain is always properly tensioned and the tension of the chain is automatically maintained. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rock drill, the combination comprising a guide providing parallel guideways lying in common transverse planes, a drill hammer motor guided on said guide for movement along the guideways thereof, a flexible control element attached to said guide and extending along the bottom of said guide longitudinally between said guideways, a rotary control member carried by said hammer motor and arranged with its axis of rotation lying in a transverse plane in parallelism to the planes of said guideways, said control member engaging said flexible control element, a direction controlling device carried by said hammer motor above the guide guideways, and operative connections extending between the guide guideways, for connecting said control device to said rotary control member.
2. In a rock drill, the combination comprising a guide providing parallel guideways lying in common transverse planes, a drill hammer motor guided on said guide for movement along the guideways thereof, a flexible control element attached to said guide and extending along the bottom of said guide longitudinally midway between said guideways below the plane of the latter, a rotary control member carried by said hammer motor and engaging said flexible control element, a second rotary control member carried by the drill hammer motor and arranged in planes above the guide guideways, a direction controlling device associated with said second rotary control member, and an endless drive chain extending between the guide guideways for connecting said rotary control members in driving relation.
3. In a rock drill, the combination comprising a guide providing parallel guideways lying in common transverse planes, a drill hammer motor guided on said guide for movement along the guideways thereof, means for feeding said motor along said guide guideways including a flexible feed control element extending along the bottom of said guide longitudinally between the guideways thereof, a rotary control member journaled on said hammer motor on a transverse axis below the top of said guide, said axis of rotation of said control member being disposed parallel to the planes of said guideways, a second rotary control member journaled on said hammer motor on a parallel axis above the top of said guide, and operative driving connections between said rotary control members, said connections extending within said guide between the guideways thereof.
4. In a rock drill, the combination comprising a guide providing parallel guideways, a drill steel actuator movable along the guideways of said guide, a flexible feeding element extending longitudinally along the bottom of said guide midway between the guideways thereof, a rotary control member carried by said drill steel actuator and arranged within said guide between the guideways thereof, said rotary member engaging said flexible element, a control mechanism carried by said actuator and arranged outside of said guide, and operative connections between said control mechanism and said rotary member, said connections extending into said guide between the guideways thereof at one side of said rotary member.
5. In a rock drill, the combination comprising a guide providing parallel longitudinal guideways disposed in common transverse planes, a hammer motor guided on said guide for movement along said guideways and having jars imparted

thereto during the operation thereof, and means operated by said jars for feeding said hammer motor step by step along said guide, said feeding means including a flexible feed control element arranged longitudinally of said guide midway between the sides thereof, a rotary control member engaging said flexible control element and arranged with its axis of rotation parallel to the planes of said guideways, a control mechanism for controlling the direction of rotation of said rotary member, resilient means for automatically tensioning said flexible element including a tensioning element arranged longitudinally midway between the sides of said guide at one end thereof and guided for longitudinal movement relative to said guide, and an automatic grip device associated with said longitudinally movable tensioning element for permitting free movement of the latter longitudinally in a direction to tighten said flexible element while precluding movement in the opposite direction thereby automatically to maintain said flexible element under tension.

6. In a rock drill, the combination comprising a guide providing spaced apart parallel longitudinally extending guideways, a drill hammer motor guided on said guide for movement along said guideways, a flexible control element attached to said guide and extending within said guide longitudinally along the bottom thereof midway between said guideways, a rotary control member carried by said hammer motor and engaging said flexible element, a direction controlling device carried by said hammer motor externally of said guide, said control member and said controlling device being arranged on parallel transverse axes arranged parallel to the planes of said guide guideways, and operative transmission connections between said rotary control member and said controlling device, said connections extending from the exterior of said guide through the space between said guideways into said guide.

CHARLES F. OSGOOD.
